LINGERIE CLASP

Filed July 6, 1927

UNITED STATES PATENT OFFICE.

MARY E. KINTZ, OF LOS ANGELES, CALIFORNIA.

LINGERIE CLASP.

Application filed July 6, 1927. Serial No. 203,747.

- My invention relates to a lingerie clasp and has for its principal object the provision of a relatively simple, practical and inexpensive device that is especially designed for engaging and holding in proper position the shoulder straps of lingerie, said device functioning as a readily detachable and flexible connection between lingerie straps and the shoulder portion of an outer garment.
- 10 The subject matter of my present application is an improvement upon the lingerie pin disclosed in my co-pending application for U. S. Letters Patent, filed April 11, 1927, Serial Number 182,767.
- 15 Further objects of my invention are to provide a lingerie clasp that includes a loop or eyelet formed from a single piece of wire or the like, which loop or eyelet is constructed so that it may be threaded or inserted through 20 a portion of the outer garment, and serve as a point of attachment for a clasp that engages the shoulder straps of lingerie, and further, to provide a device of the character referred to that may be easily and quickly manipulated 25 when applied to or detached from an outer garment and lingerie straps, and, further to provide a lingerie clasp that is inexpensive of manufacture, and which will be very effective 30 in performing the functions for which it is intended.
- With the foregoing and other objects in view, my invention consists in certain novel features of construction and arrangement of parts that will hereinafter be more fully described and claimed and illustrated in the accompanying drawing, in which—
- Fig. 1 is a perspective view of the shoulder portion of a garment with parts broken away in order to show the lingerie clasp in position on said garment, and in engagement 40 with the shoulder straps of lingerie.
- Fig. 2 is a top plan view of the clasp.
- Fig. 3 is a side elevational view of the clasp.
- Fig. 4 is an enlarged view showing the wire 45 loop or eyelet engaged in the shoulder seam of an outer garment.
- Fig. 5 is a perspective view of the spring clasp forming a part of my invention, and which engages the shoulder straps of lingerie.
- 50 Fig. 6 is a perspective view of a modified form of the shoulder strap engaging clasp.
- Fig. 7 is a detail sectional view through the end portion of a modified form of the strap engaging member of the device.
- 55 That member of the device that engages the shoulder portion of an outer garment is formed from a single piece of wire that is bent to form a pair of parallel members 10 and 11, the same being spaced a slight distance apart, and at one end these parallel members are connected by a portion of the wire that is bent to form a substantially triangular loop or eyelet 12, the outer portion of which 13 is preferably straight and occupies a position substantially at right angles to the plane occupied by the members 10 and 11.
- The end of member 10 is bent inwardly so as to form a short inturned coil 14, and the outer portion of member 11 is bent around said inturned coil 14 in the same plane therewith, thereby forming a return bend 15, and from this return bend, the terminal portion of the section of wire is bent to form a straight member 16, that lies directly against the outer side of member 10. The end of member 16 is pointed as designated by 17 in order that it may readily pass through fabric.
- The lingerie strap engaging member of the clasp is formed from a narrow strip of sheet metal having a certain degree of resiliency, and this strip of metal is bent at its center to form a straight member 18, the free end of which is bent inward to form a short curved seat 19.
- The opposite portion 20 of the clasp is spaced apart from and overlies member 18, and the free end of said member 20 is rebent outwardly to form a hook 21, the terminal portion 22 of which is bent outwardly to a slight degree and the space between this outwardly bent terminal portion and the adjacent portion of member 20 is approximately equal or a slight degree less than the diameter of the wire forming the loop or eyelet member of the clasp. Thus the straight portion 13 of said loop or eyelet member may, with slight pressure, be forced beneath the terminal portion 22 of the hook when the parts of the clasp are assembled or disconnected.
- By bending the end of member 18 inwardly and bending the end of member 20 outwardly to form the curved portions 19 and 21, said curved portions will cooperate to retain the strap engaging member in closed position when the outturned hook 21 is with slight pressure forced into the inturned curved seat 19, and at the same time hook 21 is positioned so that it may be readily engaged in eyelet 12.
- In applying the loop or eyelet member of the clasp to the shoulder portion of an outer garment the pointed end 17 of member 16 is

inserted through a portion of the fabric, on the inside of the shoulder of the outer garment, preferably a shoulder seam, and after this pointed end has been inserted through 5 the fabric it is again inserted through said fabric so as to bring the point on to the surface of the fabric, and the loop or eyelet is now manipulated so as to be completely turned around, or returned to the position 10 that it originally occupied when the pointed end 17 was first inserted through the fabric. Thus the loop or eyelet is threaded through a short portion of the goods in the shoulder of the garment, and when so arranged the loop 15 portion 12 and member 11 are exposed and the members 10 and 16 are covered by the fabric to which the device is attached.

The strap engaging member of the device, while in open position, as illustrated in Fig. 20 5, received the lingerie shoulder straps; after which the free ends of the members 18 and 20 are pressed together so that the rounded end 25 of hook 21 engages in the rounded end 19, and due to the resiliency of the metal in the parts 19 and 21 and the shape of said member 19, the hook 21 will be retained in the curved portion 19 so as to securely retain the engaged shoulder straps:

The strap engaging member of the device 30 is connected to the loop or eyelet by engaging the hook 21, in loop 12, and thus when the parts are properly connected the lingerie straps will be conveniently and comfortably retained in proper position upon the shoulder 35 of the wearer; and when desired the strap engaging member of the device may be readily disconnected from the loop or eyelet by disengaging hook 21 from the curved member 19.

In Fig. 6 I have illustrated a modified form 40 of the strap engaging member, and this form comprises a pair of straight strips of narrow metal 23 and 24 that are connected by a hinge joint 25 at one end, and the free end of member 24 being curved upward to form a seat 26 for the downwardly curved end 27 of member 23.

Where this form of device is used it is necessary to locate the lingerie shoulder straps between the members 23 and 24, and then 50 pass the curved end of one of the members 23 or 24 through the loop 12 before the ends of said members are connected by pressing the curved end 27 into the curved seat 26.

To remove the eyelet or loop from the garment it is only necessary to reversely rotate 55 said loop or eyelet so that the same makes a complete turn, and in so doing the device and the fabric in which it is seated are manipulated so that all parts of said device pass through the openings formed in the fabric when the device was applied thereto.

At the beginning of the operations incident 60 to the removal of the loop or eyelet from the fabric a portion of said fabric adjacent to one 65 of the openings through which members 10

and 16 pass is engaged beneath the inturned coil 14, thus enabling the loop or eyelet to be readily turned and removed.

In the modified construction illustrated in Fig. 7 the engaging portions of the free ends 70 of the arms of the strap receiving member are provided with coinciding depressions 28 that serve to interlock the free ends of the members when the same are closed.

A lingerie clasp of my improved construction is comparatively simple, is capable of being easily and quickly applied to or detached from a garment and lingerie straps, and provides an efficient and convenient support and retainer for the shoulder straps of under garments and the like.

It will be readily understood that minor changes in the size, form and construction of the various parts of my improved lingerie clasp may be made and substituted for those 85 herein shown and described, without departing from the spirit of my invention, the scope of which is set forth in the appended claims.

I claim as my invention:

1. In a lingerie clasp a loop formed from a single piece of wire bent to form parallel portions and an eyelet connecting said portions at one end, one end of said section of wire being pointed, the opposite end being bent to form an inturned coil, and a shoulder strap 95 engaging member provided with a hook at one end that is adapted to engage said eyelet.

2. In a lingerie clasp, a loop formed from a single section of wire the terminal portions of which are bent to form a substantially U- 100 shaped portion, and a straight leg that terminates in an inturned coil, which straight leg and coil occupy a position within the U-shaped portion, and the end of the leg of the U-shaped portion that overlies the straight leg of 105 the other terminal portion being provided with a point.

3. In a lingerie clasp an open loop formed from a single section of wire, the intermediate portion of which is bent to form an eyelet, the terminal portions of which section of wire are bent to form a U-shaped portion and a straight leg that lies inside one of the legs of said U-shaped portion, the end of said straight leg terminating in an inturned coil 115 that occupies a position inside the bend of the U-shaped portion and the end of the leg of said U-shaped portion that lies outside the straight leg, being pointed.

4. In a lingerie clasp an open loop formed 120 from a single section of wire, the intermediate portion of which is bent to form an eyelet, the terminal portions of which section of wire are bent to form overlapping members one of which is substantially U-shaped, the end of one of the legs of said U-shaped member being pointed, and the end of the other overlapping member terminating in an inturned coil 125 that occupies a position between the connected ends of the U-shaped member.

5. In a lingerie clasp, a shoulder strap engaging member formed from a single strip of resilient metal bent double to form a pair of members, one of which overlies the other, the 5 end of one of said members terminating in a curved seat, and the end of the other member terminating in an outwardly presented open hook that is adapted to engage the curved seat at the end of the other member when the device is closed. 10
6. In a lingerie clasp, the combination with an open loop formed from a single piece of wire bent to form an eyelet and the terminal portions of which section of wire overlap each 15 other, of a shoulder strap engaging member formed from a single strip of resilient metal bent double to form a pair of members, the end of one of which members terminates in a curved seat, and the end of the other member
- terminating in a hook that is adapted to engage in said curved seat when the device is closed, and to also engage in the eyelet of the open loop when the two parts of the clasp are assembled for use. 20
7. In a lingerie clasp a shoulder strap engaging member formed from a strip of resilient metal bent double to form a pair of members, one of which overlies the other, the terminal portion of one of said members being rebent to form a curved seat and the terminal portion of the other member being bent outward to form an open hook that is adapted to engage in said curved seat when the device is closed. 25

In testimony whereof I hereunto affix my 30
signature.

MARY E. KINTZ.
